SCRAPER FOR OIL WELL TUBING

Edward A. Kliewer, Longview, Tex., assignor of
one-half to R. W. Fair, Tyler, Tex.

Application August 19, 1935, Serial No. 36,848

6 Claims. (CL. 166—18)

This invention relates to well pumping equipment and it has particular reference to apparatus and design to operate in a well tubing assembly to effect removal of deposits of paraffin in the walls of the tubing.

The principal object of the invention is to provide a set of tools designed primarily for operation in the sucker rod assembly, the construction of the tools being such that the walls of the tubing assembly will be scraped clean of paraffin deposits, thus lending materially to the efficiency of the pumping elements of the well.

Deposits of paraffin on the walls of the tubing are detrimental to effective pumping inasmuch as the diameter of the tubing is greatly reduced and when the pump or traveling valve is withdrawn for the purpose of replacing worn cups, the paraffin deposits interfere with the introduction into the tubing of new and unused cups, since the diameter of the cups are greater than the diameter of the tubing, due to the paraffine deposits. Accordingly, expensive equipment is required to remove the deposits of paraffin from the walls of the tubing to enable the new and unused cups to be used therein.

Operations of this kind are expensive and require considerable time. The present invention aims therefore among its most important objects to provide a simple and inexpensive tool or set of tools adapted to be incorporated within the sucker rod assembly in spaced relationship and cooperates to scrape the tubing walls of paraffin deposits when the sucker rod assembly is withdrawn from the wells. Withdrawal of the pumping assembly is required occasionally when the cups have become worn and when withdrawn for any such purpose, the invention is operative to clean the tubing walls preparatory to introduction of new cups or substitute equipment.

With the foregoing objects as paramount, the invention has particular reference to its salient features of construction and arrangement of parts which will become manifest as the description proceeds, taken in connection with the accompanying drawing, wherein:

Figure 1 is an elevational view of the upper part of the invention assembly.

Figure 2 is an elevational view of the lower part of the assembly which is spaced well below the upper part.

Figure 3 is a transverse section on lines 3—3 on Figure 1.

Figure 4 is a transverse section on lines 4—4 on Figure 2.

Figure 5 is an elevational view of a modified

form of the invention wherein the scraper per se is removable from the mounting, and

Figure 6 is a detail view in perspective showing the scraper arranged for threaded securement to the mandrel or mounting shown in Figure 5.

Continuing with a more detailed description of the drawing, 1 designates an elongated piece of material adapted to be incorporated in a sucker rod assembly and whose upper end 2 is enlarged or greater in diameter than its middle section to define a connection for a sucker rod, not shown, and a flattened portion 3 to receive a wrench or the like. The portion 4 of the member below its midway point is enlarged in diameter and is flattened at 8 similar to the flattened portion 3 in the upper portion. These flattened portions are provided to accommodate a wrench or similar tool to effect connection and disconnection of sections of a sucker rod, the pins of one section being threaded into the box 6 of the lower end of the tool while the sucker rod 1 is adapted to be received by the pin 11 on the upper portion of the tool.

The tool shown in Figure 1 is provided with an annular protuberance or shoulder 5 having a sharpened edge 10, the latter defining an annular trough surrounding the cylindrical body 1. Communicating with this trough is an angular cleft or channel 9 of greater width at its bottom than at its top. The purpose of this channel, one of which is provided in diametrically opposite relationship in the protuberance 5 will be later explained.

The companion tool is similar in design except that two instead of one channel 9 is provided on either side of the shoulder or protuberance. This tool is likewise arranged in the sucker rod assembly well below the tool just described. It will also be observed that the grooves or channels 9 are of greater width at their lower ends than at their tops.

In operation, the pumping assembly first includes the pump barrel or traveling valve, thence the tool shown in Figure 2 connected at 12 to the sucker rod assembly and which ordinarily operates within the lower regions of the well in which a tubing of greater diameter than that nearer the surface is disposed. Next there is provided a string of sucker rods of a predetermined length, thence the tool shown in Figure 1 and another string of sucker rods to the surface. This explanation defines the assembly so that it will be understood that the tool shown in Figure 2 is known to be well below the companion tool (Fig. 1) in the well. In this order the tools are

introduced into the well and so operate as a part of the sucker or pump rod assembly.

When it is required to withdraw the pumping assembly for repairs or for any other purpose, it is obvious that accumulations of paraffin on the walls of the tubing will be engaged by the sharpened edges 10 of the members 5 and thus be scraped therefrom. This paraffin will pass through the grooves or channels 9 of the members 5 and since these channels are larger at their lower ends than at their tops, there is little likelihood that the channels will clog and become closed to further passage of paraffin or other matter.

15 The annular protuberances 5 are of such diameter as to permit of passage of liquid between them and the walls of the tubing, and since such liquid may also pass upward through the channels 9, there will be no difficulties as to construction against fluid passage around the enlarged portions of the tools.

It is apparent from the foregoing therefore that paraffin is scraped from the walls of the tubing when the tools are withdrawn from the well the sharpened edges 10 peeling off the paraffin in the upward travel of the tool while the angular channels 9 permit passage of the paraffin downward for release, the said paraffin and other deposits falling into the bottom of the hole. The walls of the tubing are thus cleaned, permitting new and unused cups to be inserted thereinto for continued operation.

The modified form of the invention shown in Figures 5 and 6 is not materially different from the construction just described and illustrated in Figures 1 to 4 inclusive, except that the annular protuberance or member 17 is interiorly threaded as shown in Figure 6 and is therefore removable from the mandrel or mounting 13.

40 The mounting 13 is provided with an enlarged upper portion 14 having a threaded pin thereon and flattened portions 15 to receive a wrench or the like. The lower portion 16 is of greater diameter necessarily than that of the portion 14 inasmuch as the threads retaining the scraper 17 must be of such diameter that the scraper can be passed over each protuberance and secured to the threads in the operative position shown in Figure 5, and in which figure the scraper is shown in transverse cross-section.

50 As in the structure shown in Figure 1, the scraper is grooved or fluted angularly to permit downward passage of paraffin and other matter as it is dislodged by the scraper.

55 Manifestly, the construction shown is capable of considerable modification and such modification as is considered within the scope and mean-

ing of the appended claims is also considered within the spirit and intent of the invention.

What is claimed is:

1. A tubing scraper comprising a body having an annular shoulder of greater diameter than the body and tapered at its base, said shoulder being provided with a pair of diametrically opposite, angularly disposed channels terminating at their upper ends in an annular cavity having sharpened edges. 5

2. A tubing scraper comprising a member having an annular protuberance of slightly less diameter than that of said tubing and provided with an annular cavity having a sharpened edge in close proximity to the walls of said tubing and further having diametrically opposite channels whose edges are angularly disposed with respect to the longitudinal axis of said protuberance. 10 15

3. Apparatus for scraping paraffin from well tubing comprising tools in spaced relationship, each having annular shoulders provided with annular cavities at their upper ends having angularly sharpened edges, said shoulders being further provided with diametrically opposed grooves in angular relationship with the longitudinal axis of said tools and communicating with said cavities. 20 25

4. Apparatus for scraping paraffin from the walls of well tubing comprising units arranged for incorporation in the pump rod assembly of said well in spaced relationship, each having angularly protruding shoulders provided with annular cavities with sharpened edges surrounding their upper portion in closely spaced relationship with the walls of said tubing, said shoulders further having channels in diametrically opposed relationship and in angular position with respect to the longitudinal axis of said units. 30 35

5. A scraper for well tubing including a member arranged for suspension in said tubing and having a shoulder defining an annular cavity provided with a sharpened edge in close proximity to the walls of said tubing and further having grooves for extraneous matter extending at angles with the longitudinal axis of said member. 40 45

6. A scraper for well tubing comprising an elongated member having a shoulder intermediate its ends of slightly less diameter than that of the inside of said tubing and provided with a sharpened upper edge, defining an annular cavity, said shoulder further having passages whose axes are at an angle relative to the axis of said elongated member and communicating with said cavity, for disposing of matter removed from the tubing walls thereby. 50 55

EDWARD A. KLIWER.
